DESIGN FOR A KNITTED TINSEL FABRIC

Israel Grabelsky, New York, N. Y.

Application May 21, 1936, Serial No. 62,756

Term of patent 3½ years

To all whom it may concern:

Be it known that I, Israel Grabelsky, a citizen of the United States of America, residing in city of New York, county of New York, and State of New York, have invented a new, original, and ornamental Design for a Knitted Tinsel Fabric, of which the following is a specification, reference being had to the accompanying drawing, forming part thereof.

The figure is a plan view of a knitted tinsel fabric, showing my new design.

The characteristic feature of my design resides in the tinsel depressed spots as shown and as indicated by a.

I claim:

The ornamental design for a knitted tinsel fabric, substantially as shown and described.

ISRAEL GRABELSKY.
